UNITED STATES PATENT OFFICE

DAVID R. LASIER AND JAMES P. HUME, OF CHICAGO, ILLINOIS, ASSIGNORS TO NORTON-LASIER COMPANY, OF CHICAGO, ILLINOIS, A CORPORATION OF ILLINOIS

DOOR HOLDER

Application filed March 31, 1930. Serial No. 440,385.

This invention relates to improved holding means for doors, windows and similar devices which are frequently equipped with mechanism for forcing them to a closing position 5 after being opened. In many instances, doors are equipped with closing and checking mechanism of a character to effect their closing movement under the controlled action of the checking device.

10 Such equipment has a well known and desirable function but in some installations along with the automatic closing action, it is desirable to provide means which will serve to hold the door in open position until it is 15 desired that the same be closed. Such holding means are now in wide use and are of various types and forms.

In cases where it is desired to hold the door open, in only one position, devices have been 20 used which effect a frictional binding between certain parts, such as relatively moving parts of the door and door check connecting arms.

These devices produce very serviceable results in some installations and in most instances, they are capable of adjustment whereby the single holding position in the 25 arc of swing may be selected at will, but they are capable of holding the door in only 30 that single position selected by the adjustment.

In other instances, such as with doors in hospitals, schools and similar uses, it is desirable to provide a holding means which 35 is capable of holding the door in any one of a plurality of selected positions, which positions are also capable, by adjustment, of being selected throughout the arc of swing 40 of the door. This type of device usually involves a plurality of lugs, and a suitable holding and releasing pawl, adapted for engagement with the lugs whereby the door may be held by any one of the lugs determining the desired degree of opening.

45 It is this last type of holding device, that

the present invention relates to, and more particularly, this invention relates to an improved construction of pawl and holding lug, whereby undesirable noises are eliminated which are occasioned in the operation 50 of ordinary construction of this type of mechanism.

It is contemplated that this invention be employed either with or without door checking devices as it is capable of functioning 55 as a holder, installed in connection with any means for forcing the closing movement of the door.

It is an object of this invention to provide a door holding device of the character described, which is simple in construction and may be readily and cheaply manufactured.

It is a further object to provide a door holding device which is simple and sure in its operation and capable of easy and accurate control.

It is also an object to provide a holding means which may be applied to various types of checking devices now in general use without involving any fundamental change in 70 their construction.

To this end, it is a further object to provide a pawl and lug construction capable of cooperation in a manner which will assure ready locking engagement and yet upon the 75 application of a slight closing force, will release by a quiet, uniform movement without liability of snapping, jerking or other action resulting in objectionable clicking or other noises.

These and other objects not specifically enumerated are contemplated for this invention, as will readily appear to one skilled in the art as the following description proceeds.

The description will be more readily understood by referring to the accompanying drawings, in which;

Figure 1 is an elevational view of a door check and door arm equipped with a holding

device constructed in accordance with the present invention;

Figure 2 is a plan view of Figure 1.

Figures 3 and 4 are cross sectional views taken on the line 3—3 of Figure 2 and looking in the direction of the arrows, Figure 3, disclosing the holding position, and Figure 4, disclosing an intermediate position of the mechanism in the process of release.

The accompanying drawings and the following description disclose one preferred form of the invention, but it is the applicants' intention not to have their invention limited in any respect thereby. The scope of the invention may be determined from the appended claims considered in the light of the illustrated embodiment and an appreciation of the advantages which the invention produces therein.

By referring to the drawings, it will be noted that the invention is illustrated in connection with a door closing and checking device, 10, but it is to be understood that it is capable of installation independently of a door check as described provided only that means are employed for exerting a closing force on the door, together with a suitable bracket or mounting for the holding lugs.

The door check here disclosed, is designated generally, by the numeral 10, and is illustrated of conventional design and therefore will not be further described. It is obvious that the holding means is capable of installation with any type of door checking device in connection with which means are provided for mounting the holding lugs.

The device illustrated in the drawings, comprises a door check 10, having a cover plate 11, covering the spring compartment thereof, and a spindle 11' on which the arm 13 is mounted.

It will be understood that the arm 13, is one of a pair of arms of usual design, employed for connecting the door to the door frame through the instrumentality of the door closing and checking device. Mounted on the cover plate 11 are a plurality of lugs 12 of special construction hereinafter more fully described. The lugs 12, may be provided in any suitable number and at any angular spacing one from the other, that will provide for holding the door in the various open positions desired.

In the present illustration, the lugs are formed as integral parts of the cover plate 11, extending laterally therefrom at equal angular spacing one from the other.

This form is merely one preferred form which gives predetermined holding positions to the door, but if it is desired, the lugs may be mounted adjustably, either collectively or individually.

Each lug may be independently mounted by a similar means, where the holding posi-

tions may be varied both as to position and angular distance apart.

In the arm 13, a threaded opening 14, is provided into which is threaded, the cup-like or thimble member 15.

The interior of this member is provided with a cylindrical surface adapted to slidably receive the plunger 16. The plunger is provided with a head 17 and depending lugs 18, providing a slot therebetween through which is positioned the pin 19, having its ends mounted in the openings 20, of the thimble member.

Extending across the space between the depending lugs is a bearing pin 21, on which is mounted the pawl 22, all as clearly shown in Figures 3 and 4.

A coil spring 23, is located in the thimble member with one end bearing against the top thereof and the other end in engagement with the head of the plunger. It will readily appear from this construction, that the expanding action of the spring forces the plunger downwardly and when there is no counter upward force thereon, the head of the plunger is brought in engagement with the pin 19, which limits its downward movement.

This mechanism is so positioned on the arm 13, that the pawl is located to pass over the series of lugs at a height relative thereto to bring the pawl in position for holding cooperation therewith.

The relative position of parts may be determined from Figures 3 and 4, and it will be noted that the pivoted pawl is free to swing upwardly upon engagement with the lugs, and freely pass thereover without effect when the door is moved past the lugs in the opening direction.

However, when the door is held in a position at which the lower end of the pawl is above the lug, and then permitted a slight closing movement, the end of the pawl will engage the lug in the manner shown in Figure 3, whereby the door is held.

To release the door, the door is forced in a closing direction to cause an upward yielding of the plunger as shown in Figure 4, and to release the holding engagement.

With pawls and lugs of ordinary construction in devices of this character, it has been found in practice, that the pawl after passing over dead center in the releasing movement, is caused to snap suddenly, under the influence of the spring in the direction to free its engagement which results in an objectionable clicking noise.

In the present invention, it will be noted that the pawl is somewhat tapered and provided with a rounded end 24, and the lugs are provided with cooperating rounded notches 25.

The diameter of the notches is slightly greater than the diameter of the rounded end 130

of the pawl, but it is of such depth and shape relative thereto, that engagement between the pawl and the lug is maintained until a sufficient movement has been effected to practically expend the energy stored in the spring 23, while passing over dead center.

The result is that the pawl is caused to rock slowly and uniformly from holding position until the arm 13 has swung past the 10 particular holding lug, a distance sufficient to permit the end of the lug to swing free of the cooperating notch.

It is obvious that the end of the pawl travels in an arc around the pin 21, as a center, 15 and consequently the pawl will not be released from the notch until the arm has swung to a position to locate the pin 21 in a manner to permit the arc of swing of the end of the pawl to clear the sides of the notch.

20 In operation, the door is open to any holding position that is desired, at which time the door is moved slightly past the holding position and allowed to return to catch the pawl in the lug, as shown in Figure 3. To close 25 the door, it is merely forced shut whereby to force the holding pawl past dead center after which the closing and checking device takes effect and brings the door quietly to a close, in the usual manner.

30 In the event that holding action is not desired, the door may be swung to open position by causing the pawl to pass completely over 35 the lug and fall free thereof on the opposite side whereby on the return closing movement, the pawl will ride over the lug without interference.

In the releasing action of the holding pawl it is obvious that the notched construction of 40 the lugs will cause the pawl to remain in contact therewith throughout that portion of 45 the swing of the door through which the coil spring 23 is compressed by the elevated position of the plunger, and that the pawl will finally pass free of the particular lug by a 50 quiet, easy motion.

We claim:

1. A holding device for doors comprising 50 two parts connected to a door and door frame, respectively, having relative movement upon opening and closing the door, the upper of 55 said parts being provided with a depending pawl pivotally carried on an upwardly yieldable mounting and having a rounded end, and a lug on said other part positioned for 60 cooperative holding engagement with said pawl, said lug having a substantially semi-cylindrical depression therein, of slightly 65 larger diameter than the rounded end of said pawl, a substantial portion of the surface of 70 said depression being determined by an arc, the radius of which is greater than the radius of the arc determining the contour of the 75 end of said pawl.

2. A holding device for doors comprising 80 a lug and a pawl adapted to pass thereover,

depending from a pivot carried on an upwardly yieldable mounting, said lug having a depression for engaging the end of said pawl in a substantial part of said depression being formed as a surface of a cylinder having a radius greater than the transverse dimension of the effective portion of the end of said pawl.

Signed at Chicago, Illinois, this 27th day of March, 1930.
